MEMO PAD HOLDER OR THE LIKE

William S. Sherman, Highland Park, Ill., assignor to Cory Corporation, Chicago, Ill., a corporation of Delaware

Filed Mar. 26, 1963, Ser. No. 74,145

Term of patent 14 years

(Cl. D74—1)

FIG. 1 is a top plan view of a memo pad holder or the like embodying my new design;

FIG. 2 is a bottom plan view thereof;

FIG. 3 is a rear elevational view thereof;

FIG. 4 is a side elevational view thereof, the side opposite thereto being similar in appearance; and

FIG. 5 is a front elevational view thereof.

I claim:

The ornamental design for a memo pad holder or the like, substantially as shown and described.
